UNITED STATES PATENT OFFICE

2,284,320

HINGE GUARD

Earl E. Howe, Royal Oak, Mich.

Application October 23, 1939, Serial No. 300,697

1 Claim. (Cl. 16—135)

This invention relates to hinges for automobile doors, commonly known as concealed hinges for the reason that they are concealed from view when the door is closed, and has for its primary object to improve the appearance of and more completely conceal such hinges when the door which they support is open.

In my prior applications Serial No. 200,907, filed April 2, 1938, and Serial No. 249,866, filed January 9, 1939, which have matured into Patents Nos. 2,228,876 and 2,201,490 respectively, I have disclosed hinge and body constructions similar to the construction with which this invention is concerned. Such constructions include a door frame having a well or recess in the edge which the door butts, and the hinge has a plate member mounted on the bottom wall of this well or recess. Supported by the plate member, for swinging movement about an axis located in close proximity to the bottom of the well or recess, is a bent arm which extends through the mouth of the well or recess. The door is mounted on the outer end of the arm and because the axis of swinging movement of the arm is spaced inwardly of the door frame from the plane of the butting door and frame members the resulting swinging movement is such that the door clears the frame during opening or closing movement.

When the door is closed the well or recess is covered and concealed, of course, but when the door is open the well or recess is uncovered and exposed. This is objectionable from the standpoint of appearance as well as for several other reasons. Persons entering or leaving the automobile body are liable to insert their fingers therein and under such circumstances movement of the door causes the hinge to injure the fingers. The relatively movable hinge parts being exposed makes it possible for clothing of the occupants to brush the same, which of course is undesirable, and when the door is moved with clothing or other foreign articles in the well or recess the hinge becomes distorted so that the door does not hang or swing properly.

The main object of this invention, more specifically stated, is to provide guard means for closing or covering the mouth of the well or recess when the door is in its open position, to thereby overcome the objections above mentioned.

Another object is to teach alternative formations of the guard means. In this respect the invention teaches the formation of a guard which may be directly mounted on one of the moving parts of the hinge for movement into and out of the opening incident to opening and closing

of the hinge, and also teaches the formation of a guard so constructed that it may swing into or out of the opening according to the position of the hinge, and as a result of contact of a moving hinge part therewith. The last mentioned guard has an added advantage in that it may be swung aside to permit lubricating of the hinge.

Another object is to provide guard means which functions to limit swinging movement of the door.

Other objects and advantages will become more fully apparent as reference is had to the accompanying drawing wherein my invention is illustrated, and in which:

15 Fig. 1 is a horizontal cross section of a fragment of an automobile body and door, illustrating a hinge equipped with a guard.

Fig. 2 is a similar section, with the door in its open position.

20 Fig. 3 is a section, similar to Fig. 2, illustrating an alternative form of guard, and

Fig. 4 is a fragmental section illustrating a guard which functions also as a door check.

More particularly, 1 designates a hollow door pillar of an automobile body, the pillar having an opening 2 in the edge thereof providing an entrance to the interior of the pillar. Spaced inwardly from the edge of the pillar in which the opening 2 is formed is a hinge supporting plate 3. The sides of the pillar and the plate 3 form a well or recess for the reception of the hinge parts.

The hinge comprises a main plate member 6 secured to the supporting plate 3 by screws 4 and a reinforcing member 5. The plate member 6 supports a hinge pintle 7, arranged in close proximity to one edge thereof, and thereby disposed in close proximity to the supporting plate 3 which constitutes the bottom wall of the well or recess. Swingably supported on the pintle 7 is an arm 8 which extends outwardly through the opening 2. The door 9 is mounted on the outer end of the arm 8.

The arm 8 is of the "hook-arm" type, or, in other words, is so bent that when the door is closed one portion of the arm lies substantially parallel to or in close proximity with the plate member 6 while the portion 10 extends at almost a right angle thereto and outwardly through the opening 2. The length of the first mentioned portion, which is immediately adjacent the hinge pintle 7, is such that when the door is swung from a closed position to an open position the portion 10 passes entirely through the opening 2. When the door is closed the arm portion 10

resides in close proximity to the edge 11 of the opening 2 and when the door is opened the portion 10 clears the edge 12 of the opening 2. This formation and mounting of the hinge causes the door to swing clear of the pillar 1 when it is moved to its open position.

With a hinge and body construction such as above described, movement of the hinge arm 8 to a position supporting the door in an open position results in an open space between the edge 11 and the arm 8. This invention provides a guard for closing this space.

The guard as shown in Figs. 1 and 2 comprises a plate having one portion 13 thereof secured to the outer face of the arm portion 10 by screws 14, one of which is shown, and having another portion 15 projecting inwardly into the pillar 1. To accommodate the projecting portion 15 the supporting plate 3 is bent to form a suitable recess 16. When the door is closed the projecting portion 15 is housed in the pillar 1 and the recess 16 and when the door is opened the arm 8 carries the portion 15 into the opening 2, as illustrated in Fig. 2.

In Fig. 3 the guard 17 is composed of a flexible member mounted on the marginal edge 12a of the opening 2a and is adapted to be swung or brushed aside through contact of the hinge arm 8a therewith. That is, the guard 17 normally moves to a position closing the opening 2a when the door is open, and may be flexed to permit the bent arm 8a to enter the pillar well or recess through the opening 2a. The guard 17 is preferably formed of rubber and is provided with self-retaining formation 18 such that it may

be hooked over the marginal edge 12a to retain itself thereon.

The guard 17, although flexible, prevents accidental insertion of fingers into the well or recess, and also guards against insertion of foreign elements or contact of clothing therewith. It may be forced backwardly, however, to enable access to the hinge for lubricating the same.

Fig. 4 illustrates a guard 19, similar to that shown in Figs. 1 and 2, having a hook formation 20 adapted to engage the hook shaped marginal edge 12b of the opening 2b. The guard, in this case, has the added function of operating as a door check, or in other words, it functions to limit swinging movement of the door.

What is claimed is:

A hinge guard for use in an assembly wherein a hinge having a bent arm is mounted in a pillar recess in such manner that one portion of the arm is swung to one side of the mouth of said recess and a second portion is swung to a position substantially parallel to the face of the pillar, said guard comprising a sheet metal plate having one end portion adapted to be attached to said second portion of said arm and another free end portion adapted to extend outwardly in the nature of a substantially smooth continuation of said second arm portion, said free end portion of the plate being of a length such as to substantially completely cover the mouth of the opening when the second arm portion is substantially parallel to the face of the pillar, said free end portion terminating in a hook adapted to engage a portion of the pillar to check swinging movement of the arm.

EARL E. HOWE.
